Elemir J. Ney, of Lowell, Mass.
Assignor to
The Lowell Manufacturing Company.
Letters Patent No. 1543, dated Feb. 25, 1862.

The schedule referred to in these Letters Patent and making part of the same
is all whom it may concern:

Be it known that I, Elemir J. Ney, of Lowell, in
the County of Middlesex and State of Massachusetts, have originated
and designed a new Pattern for Carpets or other fabrics, of which the fol-
lowing is a full, clear and exact description, reference being had to the
accompanying drawings, making part of this specification.

In Corner A. are halves of two large flowers, which,
when the design is matched, form a figure of four flowers with branch-
es or sprigs running between. Corner B. is a quarter of an eight si-
ded figure composed of small regular work.

Corners 1 and 2. when matched from a twelve
pointed block in the centre of which is a cross surrounded by small
lines and dots,

Fig. C. is one half of a block similar to that formed by
matching figs. 1 and 2. Running from corner 1. to fig. C. are two
bars enclosing a scroll 3. The group of flowers and leaves 4. are
enclosed in the same manner by bars running from corner 2. to
fig. C. The space at the side between corners 1 and 2. is occupied
by a number of various sized blocks.

Small sprigs radiate from the smaller blocks
and occupy the spaces between the larger ones.

The colors employed for the different portions of
